C. E. McMANUS

PLUNGER FOR CORK SLAB PACKING MACHINES

Filed Jan. 17, 1924

Fig. 1.

Fig. 2.

Charles E. McManus INVENTOR

Frank P. Wentworth
his ATTORNEY.

UNITED STATES PATENT OFFICE.

CHARLES E. McMANUS, OF NEW YORK, N. Y.

PLUNGER FOR CORK-SLAB-PACKING MACHINES.

Application filed January 17, 1924. Serial No. 686,799.

To all whom it may concern:

Be it known that I, CHARLES E. McMANUS, a citizen of the United States, residing at the borough of Manhattan, in the city, county, and State of New York, have invented certain new and useful Improvements in Plungers for Cork-Slab-Pack ing Machines, of which the following is a specification, reference being had therein to the accompanying drawings, which form a part thereof.

My invention relates to plungers for cork slab packing machines, and more particularly to plungers for machines of this type in which cork composition, consisting of granular cork and a thin coating of a binder or adhesive, is delivered in succeeding measured quantities to within a mold, each charge being compacted prior to the delivery of the succeeding charge, by a reciprocatory plunger.

Cork slabs to be packed in a machine in which a plunger embodying my invention is used, are extensively produced at the present time, for slicing into sheets of the required thickness for use in the production of gaskets and other articles.

The purpose of my invention is to provide a plunger for use in machines for making such slabs, so constructed that each charge of cork composition may be more effectively subjected to the compacting pressure by the plunger, and thus ensure greater uniformity in the density of the compacted mass throughout a mold, and substantial uniformity in the slabs compacted in different molds, and thus avoid wastage due to possibility of the production of sheets having in parts thereof small surface voids, or small holes passing through portions of such sheets of cork sliced from such a slab.

The imperfections above referred to necessitate a careful inspection of each sheet of composition cork sliced from a slab, and interfere with the subsequent handling of the sheets in the production of gaskets or other articles.

A plunger embodying my invention is so constructed that upon its engagement with each charge of cork composition, it will divide the charge and compact this charge as a result of a combined vertical and lateral pressure and thus not only ensure an effective increase in the compacting area of the plungers, but a reduction in the volume

of cork composition acted upon by any part of the plunger, in a manner to permit the effective application of the pressure to a relatively small mass of the composition.

The construction of the plunger is such that a more effective compaction is secured about the vertical center or core of the compacted mass, and adjacent both side surfaces thereof, than is attained by plungers heretofore used, these being the portions of the slab where imperfections, if they exist, will most likely be present.

The invention consists primarily in a plunger for cork slab packing machines substantially rectangular in cross-section, of greater width and height than thickness, and having a transversely tapered end adapted to be forced into a mold, whereby the pressure applied through the plunger divides a charge of cork composition and applies a compacting pressure to the divided charge vertically and toward both sides of the mold; and in such other novel features of construction as are hereinafter set forth and described, and more particularly pointed out in the claims hereto appended.

Referring to the drawings,

Fig. 1 is a front view of a portion of a plunger embodying my invention and of the actuating means therefor by which the plunger is reciprocated and by which the desired pressure is applied to the plunger, the mold being shown in vertical section; and

Fig. 2 is a perspective view of the lower portion of the mechanism shown in Fig. 1, illustrating the operative effect of the plunger during the compacting interval.

Like letters refer to like parts in both of said views.

In the embodiment of my invention shown in the drawings, *a* indicates a portion of a mold in which the cork composition used in forming the slab, is compacted, succeeding charges of such composition being delivered to within the mold, and each charge being of substantially the same volume. Since the compacting pressure is fairly heavy, the side walls of the mold are reinforced as shown, to prevent bulging of these walls.

The dimensions of the mold cavity are such as to form a slab of from one and one-half to three inches in thickness, about thirty inches in width and about twenty inches in

height, although these dimensions may be varied. Ordinarily, however, it is impracticable to have these slabs of a thickness greater than three inches, and it is preferable 5 to limit them to the thickness of about one and one-half inches, since this thickness permits the most effective baking or vulcanization of the material of the slab, and avoids 10 possibility of injury by the heat to the composition adjacent the surface of the slab as a result of the prolonged application of heat in the baker or vulcanizer.

During the compacting operation, a reciprocatory plunger or ram *b* is forced within 15 the mold after the delivery of each charge of cork composition thereinto, this plunger being reciprocated through a mechanism, a portion of which is shown at *c*.

A plunger embodying my invention has the 20 lower end thereof tapered as shown, thus producing a narrow, horizontal compacting surface *d* and converging side surfaces *e* and *f*. When the slab to be produced is approximately one and one-half inches, the total 25 thickness of the plunger will be approximately that of the slab to be produced, due allowance being made for the proper clearance between this plunger and the side walls of the mold cavity so as to secure a free 30 sliding fit and avoid likelihood of interference with the plunger action by small particles of cork or adhesive on the walls of the cavity.

With a plunger of the dimensions above 35 referred to, the flat, compacting end surface *d* will be approximately one-quarter of an inch in width and the converging side surfaces *e* and *f* will extend therefrom at an angle so as to be of a height of approximately 40 two inches, or extending at an angle of approximately 30° to the vertical center of the plunger. If the angle of divergence of each surface from the vertical angle is greater than 30° , the likelihood of imperfections 45 in the slab increases, while if this angle is decreased beyond that specified, I have not found that any beneficial results are attained.

As each charge of cork composition is delivered within a mold, it will be in a loose mass, and the top thereof will be substantially level. As the plunger *b* is forced 50 downwardly, the narrow vertical edge thereof will enter this loose mass adjacent the vertical center of the mold cavity, and will 55 divide it, spreading it toward the side walls of the mold. The flat lower compacting surface *d* by its downward pressure will force the cork upon opposite sides thereof, upwardly until the space between the converging side compacting surfaces *e* and *f* and the sides of the mold *a* will be completely 60 filled with the composition, which will occur before there has been any material compaction of the cork below the surface *d*.

When the triangular bodies of cork upon the opposite sides of the mold have been thus completely formed, the continued descent of the plunger *b* will exert the final compacting pressure which will thus be 70 downwardly below the surface *d*, and to a certain extent below each of the surfaces *e* and *f*, and outwardly of these latter surfaces as a result of the wedging action developed 75 by said surfaces. The configuration of the end of the plunger will thus not only cause compaction of the composition downwardly and laterally of the mold, but by reason of the increased compacting areas, will secure 80 a more effective compacting pressure to the composition contained in each charge, and the application of a direct pressure to smaller volumes of each charge, and a direct compaction to a greater quantity thereof.

After the initial charge has been delivered 85 to the mold and compacted, the portions of the previously compacted charge forming the wedge-shaped body will, by reason of the configuration of the end of the mold, receive a further compacting action through 90 the composition of the succeeding charge, and the conditions within the mold will be such as to secure a firmer bonding of the composition of succeeding charges by reason 95 of the increased contacting surface areas between such charges.

It is not my intention to limit the invention to the precise angle of divergence of the compacting surfaces *e* and *f* nor to the width of the compacting surface *d*, since 100 such will vary with variances in other dimensions of the plunger or ram, and may be varied where the quality of the cork in the composition, or the quality of the slabs produced require different degrees of density 105 in the product.

Having described the invention, what I claim as new and desire to have protected by Letters Patent, is:

1. A plunger for cork slab packing machines substantially rectangular in cross-section, of greater width and height than thickness, and having a transversely tapered end adapted to be forced into a mold, whereby the pressure applied through the plunger divides a charge of cork composition and applies a compacting pressure to the divided charge vertically and toward both sides of the mold.

2. A plunger for cork slab packing machines substantially rectangular in cross-section, of greater width and height than thickness, and having a flat compacting area upon opposite sides of the vertical center of the plunger, and angularly disposed compacting areas upon opposite sides of, and converging from the sides of the plunger towards, said flat compacting area, whereby the pressure applied through the plunger divides a charge of cork composition and

applies a compacting pressure to the divided charge vertically and toward both sides of the mold.

3. A plunger for cork slab packing machines substantially rectangular in cross-section, of greater width and height than thickness, and having a flat compacting area adjacent the vertical center of the plunger, and symmetrically arranged, angularly disposed compacting areas upon op-

posite sides of, and converging from the sides of the plunger towards, said flat compacting area, whereby the pressure applied through the plunger divides a charge of cork composition and applies a compacting pressure to the divided charge vertically and toward both sides of the mold. 15

In witness whereof I have hereunto affixed my signature this 9th day of January, 1924.

CHARLES E. McMANUS.
